BICYCLE FRONT FORK

Donald A. Wolf, Dayton, Ohio, assignor to The Huffman Manufacturing Company, Miamisburg, Ohio, a corporation of Ohio

Filed Apr. 1, 1969, Ser. No. 16,533

Term of patent 14 years

Int. Cl. D12—14

U.S. Cl. D90—9

FIG. 1 is a side view of my new design for a bicycle front fork;

FIG. 2 is a front view thereof; and

FIG. 3 is a plan view thereof.

The portion of the bicycle shown in broken lines in FIGS. 1 and 2 is included for illustrative purposes only.

I claim:

The ornamental design for the bicycle front fork, substantially as shown and described.
